MARCENUS M. WINNINGHAM, OF SEATTLE, WASHINGTON, ASSIGNOR OF ONE-FOURTH
TO PIERRE BARNES, OF SEATTLE, WASHINGTON.

ASSORTING-MACHINE FOR CANNED GOODS.

1,220,922.

Specification of Letters Patent. Patented Mar. 27, 1917.

Application filed February 23, 1916. Serial No. 79,837.

To all whom it may concern:

Be it known that I, MARCENUS M. WINNINGHAM, a citizen of the United States, residing at Seattle, in the county of King and State of Washington, have invented certain new and useful Improvements in Assorting-Machines for Canned Goods, of which the following is a specification.

This invention relates to machines for assorting canned goods of different weights; and its object is the provision of a machine of this character which will perform its office with accuracy and in a rapid manner.

The invention consists in a machine having a conveyer for first feeding cans to the pan of a weighing scale which is regulated to be depressed by an article of predetermined weight so as to enable the same to pass unobstructedly beneath the controller of an ejector, and thence be carried by said conveyer to the place of delivery for cans of correct weight; the cans of deficient weight being incapable of depressing the scale pan, encounter said controller, which is thereupon influenced to render effective power-driven devices to actuate the ejector for withdrawing the light weight articles from the pan and transferring them to a place provided therefor.

The invention further consists in the novel construction, adaptation and arrangement of parts, as will be hereinafter described and claimed.

In the accompanying drawings, Figure 1 is a plan view of a can-assorting machine embodying my invention. Fig. 2 is a view partly in side elevation and partly in longitudinal section of the same, said section being taken substantially through 2—2 of Fig. 1. Fig. 3 is a transverse section through 3—3 of Fig. 2. Fig. 4 is a detail horizontal section through 4—4 of Fig. 2 of the segment-wheel drive for a can ejector.

As illustrated, the machine is provided with a frame 5 having a platform 6 in which are openings 7 to accommodate scale pans 8. Two of these pans are shown, each of which is supported upon an upright stem 8¹ extending through a guide 9 provided on a bracket 9¹ secured to or formed integral with the platform 6.

10 represents a scale beam fulcrumed at 11 and connected from one of its arms by a link 12 to the associated pan, the other arm carrying an adjustable counterweight 10¹.

Journaled in bearings provided in hanger attachment 5¹ of the frame and in proximity to the outer sides of the openings 7, are upright shafts 13 having secured thereto, as by set screws 14, at selected elevations, hubs 60 15 from which extend oppositely directed horizontal arms 15¹ which will be herein-after designated as controllers. Subjacent to the latter and extending from diametrically opposite sides of the respective shafts 65 13 and in rectangular relations with the controllers, are fingers 16¹, hereinafter designated as ejectors. These ejectors are desirably curved at their extremities as indicated by 16² in Fig. 1.

70 Fixedly secured to each of the shafts 13 is a sector-gear 17 which, as shown in Fig. 4, is provided with teeth 17¹ and 17² disposed circumferentially with alternating concavities 17³ and 17⁴.

75 Coöperating with gear 17 is a spur-gear 18 mounted on an upright shaft 19. The spur-gear 18 is arranged with respect to a sector gear 17 so that the teeth of the former will revolve within a concavity, as 17³, of the 80 sector-gear when the sector-gear is idle; but when the sector-gear is affected by a slight rotary movement to have one of its teeth engage the spur-gear, the latter will serve to rotate the sector-gear until the other concavity, as 17⁴, of the sector-gear is presented to the spur-gear and the sector-gear again becomes idle, and so on.

85 The spur-gears are rotated continuously during the operation of the machine 90 through the agency of bevel-gears 19¹ mounted on the respective shafts 19 being driven by bevel-gears 20 upon a transverse shaft 20¹ which, in turn, is driven from a shaft 21, as by a chain 22 passing about 95 sprocket wheels 20² and 21¹ on the respective shafts.

90 The shaft 21 may be driven in any suitable manner, a power belt 23 being shown passing about a pulley 21² on the shaft. 100

24 represents a conveyer chain provided with carrier attachments 24¹ and passing about sprocket wheels 25 and 26 mounted upon transverse shafts 25¹ and 26¹ at opposite ends of the platform. Said chain 105 has a lead 24² above the machine platform 6 and is guided to travel between the openings 7.

110 The chain 24 is given an intermittent movement in the direction indicated by ar-

row α , by suitable means, as by a pawl 27 carried by a crank-pin 21³ of the power-driven shaft 21 actuating a ratchet wheel 25² provided on the shaft 25¹.

5 Extending upon one end of the platform 6 are the discharge ends of inclined can-feeding chutes 28 arranged to deliver cans into the path of the conveyer carriers. An inclined delivery chute 29 for cans of correct 10 weight is provided at the other end of the platform, while light weight cans are discharged from the platform by means of chutes 30 at opposite sides of the platform and adjacent to the respective scale pans.

15 The operation of the invention may be explained as follows:

The cans to be assorted are fed from chutes 28 to the table or platform 6 and are thereupon advanced by a succession of movements through the agency of the intermittently operated conveyer 24 to the respective scale pans 8. When a can of sufficient weight is thus brought onto a scale pan, the latter will be depressed, and in the next forward motion of the conveyer, will be carried forward below a controller 15¹ and will ultimately be delivered by the conveyer into the discharge chute 29.

30 A can of insufficient weight to depress a scale pan, however, will in traversing the same, encounter one of the controllers 15¹ which is thereby swerved to effect a slight rotation to the associated shaft 13 to effect the engagement of the sector-wheel 17 thereof with the power-driven master-gear 18, resulting in the latter rotating the shaft 13 until a series of teeth, 17¹ or 17², thus engaged have been utilized to cause the sector-gear to make one-half of a rotation and present a cavity 17⁴ or 17³ to the gear 18.

35 During such an occurrence, the ejectors 16¹ have been revolved by the shaft to cause one of the former to engage the light-weight can and push it laterally from the pan into 40 a chute 30.

The invention is of simple construction and in operation the weights of the cans effect the lowering of the heavier ones below a controller to be carried away by the 45 conveyer without influencing the ejecting devices which are rendered operative only by light-weight cans.

50 It is to be understood that the elevation of cans with reference to a controller is governed by the scales as they may be influenced, or otherwise by the weights of the cans.

The assorting devices proper are, upon occasion, caused to be operated by power-55 actuated means applied for heavy cans through the agency of the conveyer and for light cans through the coöperation of the conveyer and an ejector to impart an initial movement through a controller to a sector-gear to render the same subject to a power-

driven spur gear which then asserts itself to react through the medium of the sector-gear to cause an ejector to expel the can of deficient weight.

The controller arms 15¹ may be adjusted 70 to accommodate cans of different heights and whose weights are to be tested, and the weight at which a scale will operate may be regulated by adjusting its counterweight 10¹ on the scale beam.

75 What I claim, is—

1. In an assorting machine, a platform, a scale having a pan operable therein, an ejector-arm, normally inoperative means for actuating said arm, means to convey cans to and upon the pan of said scale, and a controller finger operatively connected with said ejector-arm and engageable by a can having a weight insufficient to depress the scale-pan thereby imparting an initial movement to the ejector-arm and rendering said first-named means capable of influencing the ejector-arm to remove such can from the pan.

80 2. An assorting machine having a weighing scale adjusted to have its pan depressed only by a can of a selected weight or of a weight in excess thereof, means to progressively carry cans to and across said scale-pan, and means for ejecting light-weight 85 cans from the scale-pan, such means comprising an ejector, a device coupled therewith and engageable by a light-weight can, and power-driven means rendered operable by a can engaging said device whereby said 90 ejector is caused to remove a can from the scale-pan and restore said device into operative position.

3. In an assorting machine, a platform, a weighing scale having a pan operable in an 105 opening of the platform, a conveyer for the transmission of cans on the platform to be weighed upon the scale-pan, a vertical shaft, a sector-gear provided on said shaft, a power-driven spur-gear, an ejector finger extending from said shaft, and a controlling arm provided on the shaft and disposed at an elevation to allow the passage therebelow of a can of weight sufficient to depress the scale-pan but engageable by a 110 can of less weight whereby the progressive travel of such can will influence said sector-gear to effect the meshing of the same with said spur-gear whereupon the latter actuates the aforesaid ejector finger for the removal of the light-weight can from the scale-pan.

4. In an assorting machine, a platform, a scale having a pan extending through said platform, a conveyer adapted to transmit 125 cans to and from said scale-pan, an upright shaft rotatable in proximity to said pan, a sector-gear mounted on said shaft, a spur-gear, means to rotate said spur-gear continuously during the operation of the machine, 130

an ejector-finger provided on the shaft, a controller arm provided in superposed relation to the aforesaid finger and normally extending over the scale-pan, said arm being arranged to be subject to a can traversing the scale-pan and of insufficient weight to depress the latter whereby the shaft is influenced to cause said sector-gear to become operable with respect to the spur-gear 5 whereupon said shaft is rotated to cause said ejector-finger to effect the removal of such light-weight can from the scale-pan.

5. An assorting machine, having a platform with an opening therein, a scale provided with a pan operating in said opening, an upright shaft, an ejector-finger extending from said shaft, a sector-gear mounted on said shaft, a power-driven gear, means to convey cans across said scale-pan, and a controller-arm extending from said shaft at a predetermined height and adapted to be encountered by a can of insufficient weight to depress the scale-pan whereby said shaft is influenced to rotate the sector-gear into mesh 10 with said power-driven gear whereby the 15

latter becomes operative to actuate the shaft to cause said ejector-finger to remove such light-weight can.

6. In an assorting machine, a weighing scale, a conveyer for carrying cans to and from the pan of said scale, a shaft, normally inoperative means to afford rotary motion to said shaft, an ejector-finger extending from said shaft, a controlling arm extending from said shaft at an elevation to allow the passage therebelow of a can of sufficient weight to depress the scale-pan but engageable by a can of less weight whereby the progressive travel of the can will act through the instrumentality of said controlling arm to effect the operation of the aforesaid means to impart rotary motion to said shaft and cause the ejector-finger to remove the light-weight can from the scale-pan. 30 35

Signed at Seattle, Washington, this 14th 40 day of January, 1916.

MARCENUS M. WINNINGHAM.
